UNITED STATES PATENT OFFICE.

JOSEPH C. HACKER, OF BROOKLYN, NEW YORK.

DESIGN FOR A POCKET-BOOK FRAME.

Specification forming part of Design No. **8,049**, dated February 9, 1875; application filed January 20, 1875.
[Term of Patent 3½ years.]

To all whom it may concern:

Be it known that I, JOSEPH C. HACKER, of Brooklyn, in the county of Kings and State of New York, have invented a Design for a Pocket-Book Frame, of which the following is a specification:

This invention is illustrated in the accompanying drawing, in which Figure 1 shows a pocket-book in a closed condition with my invention. Fig. 2 shows the same pocket-book in an open condition.

Similar letters indicate corresponding parts.

My invention consists in the design of a curved flap-frame and of a rectilineal book-frame for pocket-books, the same having a series of ornamental lugs, whereby the pocket-book acquires a very handsome and distinguishing appearance.

In the drawing, the letter A designates my design of the flap-frame, which has a symmetrical curved shape. C C designate the

two pieces constituting my design of the book-frame, which have a rectilineal form, D. The parts A C C are severally ornamented with lugs a b, which are formed at the ends as well as midway between the ends of the same, as shown in the drawing.

What I claim as new, and desire to secure by Letters Patent, is—

1. The curved flap-frame A, having the ornamental lugs a, substantially as shown and described.
2. The rectilineal book-frame C C, having the ornamental lugs b, substantially as shown and described.

In testimony that I claim the foregoing I have hereunto set my hand and seal this 19th day of January, 1875.

J. C. HACKER. [L. S.]
